UNITED STATES PATENT OFFICE

2,438,364

BUNION PROTECTOR AND MEANS THEREON
FOR HOLDING THE SAME IN PLACE

Milton B. Goldbaum, Brooklyn, N. Y.

Application August 21, 1945, Serial No. 611,709

2 Claims. (Cl. 128—81)

1

My invention relates to improvements in a bunion protector and a means thereon for holding the same in place, and it consists in the novel features which are hereinafter more fully described.

One of the objects of my invention is to produce as an article of manufacture a bunion protector with a means attached thereto for holding the protector in place on the foot of the patient at a required distance from the tip of the toe at said bunion, to prevent displacement of the protector in a direction lengthwise the foot of the patient.

Another object is to prevent the said holding means from constricting the circulation of the blood in any part of the foot of the patient.

A further object is to have the said holding means in the form of a cap of adjustable length for the toe of the patient whereby to hold the protector in any desired position lengthwise of the foot of the patient.

Another object is to have the said holding means consist of a sleeve of knitted or woven material of excessive length connected at one end thereof to the protector and the other end thereof to extend beyond the tip of the toe of any patient, the said sleeve being adapted to have its excess length formed into a cap at the end of the toe by twisting and retroverting the sleeve over the end of the toe of the patient.

A still other object is to have the said protector and means thereon for holding the same in place adapted for mass production.

Another object is to have the said protector and means thereon for holding the same in place simple, durable and inexpensive.

A further object is to have the bunion protector of an improved construction as is hereinafter described.

Other objects and advantages will hereinafter appear.

I attain these objects by the bunion protector and means thereon for holding the same in place which is illustrated in the accompanying drawings or by any mechanical equivalent or obvious modification of the same.

In the drawings Fig. 1 is a plan view of the preferred initial commercial form of my bunion protector and means thereon for holding the same in place; Fig. 2 is an end view of the same; Fig. 3 is a plan view of the device after the sleeve, which is hereinafter described, has been twisted in a vertical plane through an angle of about 180 degrees; Fig. 4 is a plan view of the device after the sleeve as shown in Fig. 3 has been turned in a horizontal plane through an angle of 180 degrees

2

and the end thereof which is adjacent to the bunion protector has been retroverted over the other end thereof after the latter has been drawn over the toe of the patient at the bunion; and Fig. 5 is a plan view of an improved form of a bunion protector.

Similar numerals refer to similar parts throughout the several views.

11 designates a bunion protector which is largely 10 of standard design but has thereon extending therefrom a stub 12 which is shown as connected by means of stitches 13 to one side 14 of one end 15 of a sleeve 15—16 of excessive length which may be made of any soft and elastic material such as 15 knitted or woven fabric and the like.

The length of the sleeve 15—16 may be greater than the possible distance from the bunion of any patient to the end of his toe, and the sleeve is to extend beyond the tip of the toe when the protector is in position.

The sleeve 15—16 may be made in two sizes or widths, to fit the great or first toe and the small or fifth toe; and with the bunion protector attached to it the sleeve may be sold to the general public, if desired.

To apply the device to a toe which has a bunion thereon or thereat the end 16 of the sleeve 15—16 as shown in Fig. 1 may first be drawn on to the toe; the end 15 of the sleeve 15—16 may then be 30 turned in a vertical plane through an angle of substantially 180 degrees as shown in Fig. 3, or any other convenient angle, thereby forming a twist as at 17, and retroverted over the end 16 of the sleeve 15—16 as shown in Fig. 4, with the bunion protector retaining its position with relation to the side 14 of the end 15 of the sleeve 15—16, whereby the protector 11 with the stub 12 thereon is inverted in position with relation to the bunion; the top side of the protector in Fig. 1 becomes the 40 under side of the protector in Fig. 4.

The twist at 17 then forms a closed wall for the end 16 of the sleeve 15—16, thereby forming a cap for the end of the toe of the patient which cap 16—17 is shown as shorter than the retroverted end 15 of the sleeve 15—16.

It is evident that the length of the cap 16—17 may be varied by varying the length of the end 16 of the sleeve 15—16 which is drawn over the toe and by varying the position of the twist 17 on the 50 sleeve 15—16.

In Fig. 4 a clearance is shown between the outside of the cap 16—17 and the inside of the retroverted end 15 of the sleeve 15—16, for the sake of clearness; but in practice no such clearance is 55 necessary.

The cape 16—17 may be unmade, if desired, and remade to tighten the part of the sleeve between the toe and the protector, thereby adjusting the length of the said part, when necessary.

Instead of a sleeve a length of flexible material other than a sleeve may be employed.

The end of the sleeve 15—16 may be formed into a cap for the toe otherwise than as shown and hereinbefore described, if desired; but I prefer the construction as shown in Figs. 3 and 4 and described.

As a variation of my device the twist 17 may be omitted and the retroverted sleeve 15—16 have its end (on the left in Fig. 4) sealed or closed by means of a strip of adhesive tape or by stitching, if desired.

The formation of the cap on the end of the toe of the patient and the twisting and retroversion of the sleeve or other piece of material serve to keep the protector in a desired position on the bunion.

Standard bunion protectors are made of two thicknesses or plies of chamois 18 and 19 with pads 20 and 21 therebetween; the ply 18 has therein an opening 22; the plies 18 and 19 are stitched together at their outer edges as at 23 and around the opening 22 as at 24 and also around the convex side of the pad 20 as at 25; the stitching at 25 is too close to the pad 20 to permit any lateral adjustment of the position of the latter.

In the variation of the bunion protector which is shown in Fig. 5, the stitching at 25a around the convex side of the pad 20 is far enough from the latter to permit lateral adjustment of the pad 20, if desired.

Elevations on the outer sides of the plies 18 and 19 which are produced by the pressure of the pads 20 and 21 therebetween are shown at 26 and 27 respectively in Figs. 1 and 3 and at 28 in Fig. 4.

Other variations are possible and parts of my invention may be used without other parts; I do not, therefore, restrict myself to the details as shown in the drawings.

I claim as my invention and desire to secure by Letters Patent:

1. As an article of manufacture a bunion protector and a tubular member of soft elastic material of relatively excessive length open at the outer end thereof, and connected at the inner end thereof to the protector, said member being adapted to enclose the toe of the patient, the length of said member being greater than the possible distance from the bunion of any patient to the end of his toe, and the outer end of the said member being adapted, when the said protector is in position, to extend beyond the tip of the toe and to be twisted and retroverted over the end of the toe, whereby to keep the protector from being displaced longitudinally on the foot of the patient.

2. The combination of a bunion protector and a means thereon for holding the same in position, said means comprising a tubular member of soft elastic material of relatively excessive length enclosing the toe of the patient and connected at one end thereof to the protector, said member terminating at the other end thereof in a twisted and retroverted cover for the end of the toe of the patient formed of the excess length of the said member and placed on the end of the toe of the patient at a desired distance from the protector, thereby serving as a means of adjusting the length of said member, whereby to keep the said protector in a desired position.

MILTON B. GOLDBAUM.
